ROVING CUTTER

Gaymond E. Milligan, 614 Knipp Road, Houston, Tex.
Filed June 15, 1960, Ser. No. 36,297
11 Claims. (Cl. 30—128)

The present invention relates to a roving cutter.

Reinforced plastic articles are usually reinforced with fibers or filaments of glass and are then applied to and bonded to the particular plastic article. Roving is a rope-like material of any desired number of strands or ends of fibers, such as glass fibers. This roving is the raw material from which chopped strand mats, one of the cheapest forms of fibrous glass reinforcement for plastic articles and shapes in common use, are made.

The present invention is directed to an improvement in roving cutters for cutting roving into predetermined lengths and then separating the cut strands of roving and applying it to a plastic shape or article to be formed. It is particularly directed to such an improved roving cutter which may be held by hand and any desired quantity of the cut or chopped roving may be applied to a plastic article.

It is therefore an object of the present invention to provide an improved roving cutter which may be held by hand and which effectively and efficiently cuts roving, separates the strands and applies it to the plastic shape or form or article in one operation.

Yet a further object of the present invention is the provision of such a roving cutter in which the separated strands of cut roving may be applied to plastic material arranged in various shapes, molds and the like where it is difficult to apply roving.

Yet a further object of the present invention is the provision of a fully portable, relatively light weight, hand-held, roving cutter which cuts roving into predetermined lengths, separates the strands and applies the cut and separated strands of roving at the desired place.

Still a further object of the present invention is the provision of such a roving cutter which is effectively efficient in operation and which is readily and inexpensively operated and maintained.

Still a further object of the present invention is the provision of such a roving cutter in which the back-up roller and the cutter element are so arranged to avoid undue wear on the back-up roller and give extended cutter efficiency.

Still a further object of the present invention is the provision of a roving cutter provided with an improved cutter element in which the cutters are easily and readily replaced and adjusted.

Still a further object of the present invention is the provision of a pneumatic roving cutter which automatically and effectively lubricates the various parts of the cutter.

Other and further objects, features and advantages of the present invention will be apparent from the following description of a presently preferred embodiment thereof, taken in conjunction with the accompanying drawings, in which like character references designate like parts throughout the several views, and where

FIGURE 1 is a side sectional view of a roving cutter according to the present invention.

FIGURE 2 is a partial end view of the roving cutter looking in the direction of the arrows 2—2.

FIGURE 3 is a sectional view taken along the line 3—3 of FIGURE 1.

FIGURE 4 is a sectional view taken along the line 4—4 of FIGURE 1.

FIGURE 5 is an exploded, fragmentary, perspective view of the cutter rotor illustrating the manner of inserting and replacing the cutter blades.

2

FIGURE 6 is a view taken along the line 6—6 of FIGURE 1.

FIGURE 7 is a perspective view of the back-up roller and roving driver assembly, and

5 FIGURE 8 is a sectional view taken along the line 8—8 of FIGURE 6.

Referring now to the drawings, and particularly to FIGURE 1, the roving cutter is generally designated by the reference numeral 10 and includes a body 12 which 10 includes the various driving and cutting elements, as presently described, the handle 14 for gripping the cutter and controlling its operation, as presently described, and the outlet 16 in which the roving cut into predetermined lengths is discharged and separated on to a plastic form, 15 mold or shape to which it is desired to add chopped roving.

The body 12 is provided with the chamber 18 which is closed on each side by the cover plates 20 and 22, as best seen in FIGURE 4, for assembling the various elements of the cutter contained in the chamber 18 and for 20 making repairs, replacements and the like.

While the body 12, handle 14 and outlet 16 may be formed of any desired material, preferably it is formed of a light weight metal to give the required strength and 25 rigidity and at the same time be light enough to be handled by an operator over long periods of time without tiring. One such material is aluminum although it will be understood that any desired material may be used.

Referring again to FIGURE 1, in the body 12 there 30 are provided the air or pneumatic motor 24, the pressure roller 26, the cutter rotor 28 and the back-up roller 30 for the pressure roller 26 and cutter rotor 28.

An opening 32 is provided in the lower portion of the body 12 into which is secured the guide bushing 34 35 provided with the passage 36 for reception of roving. It is noted that the inner end of the bolt 34 and its passage 36 extend between the pressure roller 26 and the back-up roller 30 so that roving is fed between these rollers for drawing it into the chamber 18 and in contact with the 40 blade type cutters 36' carried by the cutter rotor 28 for cutting the roving.

In order to insure that the roving is directed toward the cutter rotor 28 a guide bar 38 is provided between the pressure roller 26 and the back-up roller 30.

The mounting details for the pressure roller 26, back-up roller 30 and guide bar 38 are best illustrated in FIGURE 7 to which reference is now made. A frame assembly including the sides 40 and 42 receive the shafts 44 and 46 of the pressure roller 26 and back-up roller 50 for journaling them in position. An adjustment thread 48 is provided in the boss 50 disposed in the bottom 52 of the frame for threadedly receiving the adjustment screw 54, as best seen in FIGURE 1, for adjustably supporting the back-up roller 30 with respect to the cutter rotor 28.

55 As best seen in FIGURE 6, the shaft 44 is journaled in the side plates 20 and 22 so that manipulation of the adjusting screw 54 causes the frame 41 to pivot about the shaft 44 so that the forward end of the frame 41, and hence the back-up roller 30, can be moved to and away 60 from the cutter rotor 28.

Advantageously, the frame 41 also supports the deflecting or guide bar 38 and maintains the pressure roller 26, the back-up roller 30 and the guide bar 38 in a predetermined relationship at all times.

65 The pressure roller 26 and back-up roller 30 have the inner core 27 and 29, respectively, which is covered with a resilient surface 31 and 33, respectively, such as one made of rubber, neoprene or other resilient surfaces which effectively grip the roving and move it through the cutter.

Referring now to FIGURE 5, the details of the cutter rotor 28 and cutter blades 36' and their mounting is

illustrated. The cutter rotor 28 is provided with a series of radially extending slots 25 into which are placed the cutter blades 36'. The leaf type springs 27' are also provided, only one being shown in this view, and are placed in the slots 25 along with the blades 36' which releasably hold them in place, as illustrated in FIGURE 1.

It is also noted in FIGURE 4, that the side plates 43 are secured to the sides of the cutter rotor 28, such as by the bolts 45, although they may be secured in other ways, which include the inwardly extending terminal stop members 47 which engage the chamfer 49 of the blades 36' which assist in maintaining the blades 36' in position.

Thus, the blades 36' may be added quickly and conveniently to the cutter rotor 28 by removing the side plates 43, pulling the blades 36' and springs 27' out of the slots 25, inserting new blades and the springs 27' in these slots 25 and reattaching the cover plates 43.

The details of mounting the cutter rotor 28 are best illustrated in FIGURE 4 to which reference is now made. The shafts 35 and 37 extending from each end of the cutter rotor 28 are journaled in the bearings 39 and 41, respectively, disposed in the cover plates 20 and 22. Thus, the cutter rotor 28 is rotatably supported in the chamber 18 of the body 12.

Referring again to FIGURE 1, the roving cutter is pneumatically driven, and for this purpose there is provided in the handle 14 the air inlet passage 54 having the threaded opening 56 to which is secured the air hose 58 for supplying air to the cutter from any suitable source, not shown. A trigger assembly 59 is provided which actuates the spring pressed needle valve generally indicated by the reference numeral 60.

The air passage 54 extends up through the handle 14 and is in communication with the counterbored portion 61, the air passage 62, the counterbored portion 63 at the other end of the passage 62 which receives the needle valve generally designated by the reference numeral 64. Adjustment of the needle valve 64 controls the amount of air passing into the passages 65, only one being shown, for separating the strands of cut roving and applying it to the plastic as presently described.

Referring now to the details of construction of the trigger assembly 59, a slot 66 is cut in the upper rearward portion of the handle 14 into which is pivotally secured the trigger 67 by the pivot 68. The upper end of the trigger 67 includes a projection 69 to which is secured the plunger 70 of the needle valve 60.

The plunger 70 has the needle valve element 71 on its inner end which seats against the valve seat 72 provided in the annular valve body 73 which is threadedly or otherwise secured in the counterbored portion 61, such as by the threaded area 74.

A bolt 75 is threaded or otherwise secured in the bore 76 of the valve body 73 to serve as a stop for the compression spring 77 at one end. A stop member 78 is provided adjacent the other end so that the spring 77 resiliently maintains the needle valve element 71 seated against the valve seat 72.

A series of ports 79 are provided in the valve body 73 proximate the air inlet passage 54 so that air entering the air passage 54 flows into the valve body 73.

It seems apparent that the pressure of the air against the valve element 71 and the spring 77 yieldingly maintain the needle valve element 71 against the valve seat 72 until the trigger 67 is squeezed which causes the projection 69 to move backwardly and thereby open the needle valve. This, of course, permits air to flow to the various elements as presently described. Once the trigger 67 is released, however, the combined action of the air pressure and spring 77 immediately close the needle valve 60.

It is noted that the entire needle valve assembly 60 may be removed for repairs or replacement. Of course,

suitable packing, such as the O-rings 80' and 81' at the inner and outer ends of the valve body 73 are provided to effectively seal off the assembly.

Still with reference to FIGURE 1, the needle valve assembly 64 is provided to adjust the amount of air flowing in the passages 65 and being ejected out the opening 16. As in case of the needle valve 60, the needle valve 64 is also made in a complete assembly which may be readily removed for repairs, replacements and maintenance.

An annular valve body 80 is provided which is threadedly or otherwise inserted into the counterbored portion 63, such as by the threaded area 81. A valve seat 82 is provided adjacent the interior end of the valve body 80 and a needle valve element 83 is provided on the inner end of the valve stem 84 extending from the threaded portion 85 and nut 86 which is threaded through the threaded opening 87 in the valve body 83 so that adjustment of the nut 86 adjusts the position of the needle valve element 83 with respect to valve seat 82.

The valve body 80 has the ports 88 so that air from the passage 62 flows into the valve body 83 through the valve seat 82, out the ports 88 into the counterbored portions 63 and into the passages 65 which communicate with the passages 17 in the outlet 16.

As in the needle valve assembly 60, there are provided in the needle valve assembly 64 suitable packing elements, such as the O-rings 89 and 90 to suitably pack off this valve assembly.

Referring now to FIGURE 3, the air passage 62 has a branch member 91 leading to a lubricant assembly 92 and to the air passage 93 leading to the air motor 94, as best seen in FIGURE 1.

The air motor 94 is generally a rotor provided with the helical vanes 95 and which rotor 94 is eccentrically mounted in the motor housing 96 by the shaft 97. The vanes 95 are slidably mounted in the slots 98 so that more area to the vanes is provided in the upper portion and the direction of rotation to effect rotation of the rotor 94. The air passage 91 is in communication with the rotor 94 through the end bearing plates and a slot 99 is provided to exhaust the air. Since this slot 99 is only on one side it acts as an increasing pressure exhaust in determining the direction of the motor. The air exhausted through the slot 99 enters the outlet void 100 between the motor housing 96 and the body 10. The extended void 100 permits the slot 99 to be put in any close alignment with the exhaust ports 101 without having to be too careful of choking off the exhaust. Thus, the air exhausts in a direction away from the direction in which the cut fibers are being directed by the cutter.

As best seen in FIGURE 4, the rotor blades 95 are generally helically mounted to provide a more efficient drive. A bearing ring 102 is provided which receives the shaft 103 for centering the rotor 94 in the housing 96.

The shaft 97 extending from the other end of the rotor 94 is journaled through a similar bearing 104 and has connected to its free extremity the driving gear 105.

The driving means from the driving gear 105 is housed in the gear chamber 106 at one side of the body 12.

The driving means preferably is a gear train which is best illustrated in FIGURE 8, to which reference is now made. In this figure a satisfactory gear train is provided which includes the idler 107 meshing with and being driven by the driving gear 105 which provides a gear reduction. The idler 107 engages and drives the driven gear 108 which rotates the cutter rotor 28 (FIGURES 1 and 4).

In order to provide reverse rotation to the gear 110 which drives the back-up roller so that the direction of rotation will be such that the roving is forced between the cutter and the back-up roller (FIGURE 1) the idler gear 109 engages and is driven by the idler 107, which idler gear 109 in turn engages and drives the driven gear 110 for the back-up roller. It is noted that the drive train

is such that there is no change in gear pitch speed in the driven gear 110 from the driven gear 108.

As best seen in FIGURE 4, the details of mounting the idler gear 107 and the driven gear 108 for driving the cutter rotor 28 are illustrated. The idler and reduction gear 107 is provided with the shaft 111 which is journaled in the bearings 112 at each side for rotatably supporting the gear 107 in position.

The driven gear 108 is connected to the shaft 113 extending from the cutter rotor shaft 35 and is supported by the bearing 41 as previously described.

In order to seal off the cutter rotor 28 and the chamber 18 from any lubricant, a bearing surface 114 is provided by the gear hub 115, which bearing surface 114 engages the annularly disposed packing 116 surrounding the rotor shaft 37.

With reference to FIGURE 6, the idler gear 109 and driven gear 110 for the pressure roller 26 and back-up roller 30, respectively, are secured to their respective shafts 44 and 46. In addition, the bearing surfaces 117 and 118 are provided which respectively engage the packings 119 and 120 surrounding the shafts 44 and 46, respectively, to prevent lubricant from entering the chamber in the frame 40 disposed in the chamber 18 of the body 12.

While the gear train described in some detail is preferred, any desired drive means may be utilized in which there is provided a gear reduction and in which the back-up roller 30 and cutter rotor 28 are driven at the same surface or peripheral speed.

In order to lubricate the gears, and as best seen in FIGURE 3, a lubricant reservoir 121 is provided in the upper portion of the body 12 which is closed by the threaded plug 122 being threadedly secured in the threaded area 123 of the body 12. The plug 122 is provided with an effective seal 124 which effectively prevents leakage of pressure to the outside of the body 12, but is provided with a seal 125 which permits pressure to be applied through the seal from the air line 91 into the branch lines 126 leading to the passage 127 so that pressure is applied to the lubricant in the reservoir 121.

A passage 128 is provided from the reservoir 121 leading to the gear chamber 106, as best seen in FIGURE 4 so that lubricant under pressure is always being provided to the gear chamber 106, as best seen in FIGURE 4.

A lubricant discharge port 129 is provided adjacent a rearward portion of the gear chamber 106 for removal of lubricant therefrom.

In operation, roving is inserted into the opening 36 and up between the pressure roller 26 and back-up roller 30. By merely pressing the trigger 67 air pressure is applied to the motor 94 which through the reduced gear drive drives the back-up roller 30 and cutter rotor 28 at the same speed and in the directions previously mentioned. This permits the blade edges 36' to move at the same peripheral speed with respect to the back-up roller 30 thereby preventing any cutting or undue wear on the back-up roller 30. The pressure roller 26 is free turning, the gear 109 being an idler gear, it moves with the movement of the roving and back-up roller 30. The roving is chopped into the desired lengths and the air passing out the openings 17 draw the cut roving out of the cutter, separate the strands and direct it as desired.

It is noted that the roving may be cut at any predetermined desired length merely by placement of the cutter blades 36'. Also, as the cutter blades 36' may vary in width the back-up cutter 30 may be adjusted for this differential so that effectively efficient cutting of the roving without any undue wear on the back-up roller 30 is obtained.

The amount of air provided to the outlet 65 may be varied, as previously mentioned, by adjustment of the adjusting nut 86 for whatever purpose is desired. Also, as previously mentioned the cutter is disassembled and the various parts repaired or replaced or adjusted readily and

easily. In addition, a highly efficient lubrication system is provided.

While the present invention is particularly adapted for use as a hand held mechanism, in view of its simplicity, 5 compactness and light weight, it may be utilized in fixed relation, that is it may be mounted in fixed relation, to plastic shapes, forms, molds and the like to be reinforced with roving.

The present invention therefore is well suited and 10 adapted to attain the objects and ends and has the advantages mentioned as well as others inherent therein.

While a presently preferred embodiment of the invention has been described for purposes of disclosure, numerous changes in details of construction and arrangement of 15 parts may be made which are within the spirit of the invention as defined by the scope of the appended claims.

What is claimed is:

1. A roving cutter comprising, an enclosed body, a pressure roller disposed in the body, a backup roller disposed in the body adjacent the pressure roller, a cutter rotor provided with cutting blades disposed in the body adjacent the backup roller and arranged so that roving passes between the pressure roller and the backup roller and between the backup roller and cutter rotor thereby 25 cutting the roving into predetermined lengths, said body enclosing said rollers and rotor, inlet means in the body of a size slightly larger than the roving for introducing the roving into the body and passing it between the pressure roller and the backup roller as aforesaid, an ejector 30 at the forward end of the body in communication with the backup roller and the cutter rotor and provided with air jets for ejecting the cut roving, a motor carried by the body, and drive means operatively connecting the motor with the backup roller and with the cutter rotor and driving the cutter rotor in one direction and the backup roller 35 in a reverse direction and the edges of the cutting blades and the backup roller at substantially the same peripheral speed.

2. A roving cutter comprising, an enclosed body, a pressure roller disposed in the body, a backup roller disposed in the body adjacent the pressure roller, a cutter rotor providing with cutting edges disposed in the body adjacent the backup roller, roving entering the cutter passing between the pressure roller and the backup roller and between the backup roller and the cutter rotor, said 40 body enclosing said rollers and rotor, inlet means in the body of a size slightly larger than the roving for introducing the roving into the body and passing it between the pressure roller and the backup roller as aforesaid, an ejector in the forward end of the body for ejecting the cut roving in communication with the backup roller and the cutter rotor, an air motor carried by the body, means providing air to the motor for driving the same, drive means operatively connecting the motor with the backup 45 roller and with the cutter rotor and arranged to rotate the cutter rotor in one direction and the backup roller in a reverse direction and the cutting edges and the backup roller at the same peripheral speed, and air passageways in the ejector in fluid communication with the means for providing air to the motor whereby the air jetting through the passageways draws the cut roving out of the body through the ejector.

3. The roving cutter of claim 2 where the drive means comprises a driving gear connected to the motor, a driven gear connected to the rotor cutter engaging and being driven by the drive gear, an idler gear being driven by the driving gear, and an additional gear connected to the back-up roller engaging and being driven by the idler gear, said gears being arranged to drive the cutting edges 50 and the back-up roller at the same peripheral speed.

4. The roving cutter of claim 2 including a trigger assembly, said trigger assembly including a spring-pressed needle valve assembly normally closing the means providing air to the motor but openable upon actuation of 55

said trigger assembly for providing air supply to the motor.

5. A roving cutter comprising, a body, a first chamber in the body, a pressure roller rotatably mounted in the chamber, a back-up roller rotatably mounted in the first chamber adjacent the pressure roller, a cutter rotor provided with cutting edges rotatably mounted in the first chamber adjacent the back-up roller, means in the body for feeding roving into the chamber between the pressure roller and back-up roller, said pressure roller and back-up roller feeding the roving between the back-up roller and the cutter rotor thereby cutting the roving, an air motor in the body apart from the first chamber, the body provided with an air passage for supplying air to the air motor, a discharge opening at the forward end of the body opening into the first chamber, a plurality of ports arranged about the discharge opening, air passage means connecting the ports with the air passageway for jetting air out the opening and drawing cut roving therethrough, a second chamber in the body, drive means in the second chamber connecting the motor to the back-up roller and cutter rotor for driving the same, said drive means and rotating the back-up roller and the cutting edges of the cutter rotor at the same peripheral speed, a lubricant reservoir in the body, a passageway in fluid communication with the reservoir and with the second chamber for lubricating the gear means, an additional passageway in fluid communicating from the air passage to the reservoir for applying the air pressure to the lubricant in the reservoir, and exhaust outlet means in the second chamber exhausting lubricated air therefrom.

6. The roving cutter of claim 5 including a normally closed valve assembly in the air passage openable to permit flow of air to the motor and to the ports.

7. The roving cutter of claim 6 including a choke arrangement in fluid communication with the air passage for applying air pressure to the lubricant in the reservoir.

8. A rotary cutter for roving comprising, a rotor, a

plurality of radially extending and circumferentially spaced slots, at least one blade-like cutter element disposed in at least one of the slots, and a leaf-like spring member insertable in the slots yieldingly holding the blade-like cutter member in the slots.

9. The cutter of claim 8 where the blade-like cutter members are provided with stop shoulders adjacent their sides, and including stop members secured to each side of the rotor engaging the stop members of the blade for maintaining the blades in the slots.

10. A roving cutter comprising, a first frame, a second frame mounted in the first frame, a pressure roller rotatably mounted in the second frame and provided with shaft extensions pivotally mounting the second frame in the first frame, a back-up roller rotatably mounted in the second frame adjacent the pressure roller, a cutter rotor provided with cutting edges rotatably mounted in the first frame adjacent the back-up roller whereby roving passes between the pressure roller and back-up roller and between the back-up roller and the cutter rotor for cutting the roving, means carried by the first frame for rotating the back-up roller and the cutter rotor, and an adjusting element adjustably securing the second frame to the first frame adjacent the back-up roller whereby operation of the adjusting element moves the back-up roller toward and away from the cutter rotor.

11. A rotary cutter for roving comprising, a rotor, at least one radially-extending slot in the rotor, a blade-like cutter element disposed in the slot, and a leaf-like spring member insertable in the slot yieldingly holding the blade-like cutter member in the slot.
